UNITED STATES PATENT OFFICE.

JULIUS FRANCIS ROGERS, OF ST. JOSEPH, MISSOURI.

DESIGN FOR A HITCHING-POST.

SPECIFICATION forming part of Design No. 16,306, dated September 29, 1885.

Application filed July 24, 1885. Term of patent 14 years.

To all whom it may concern:

Be it known that I, JULIUS F. ROGERS, a citizen of the United States, residing at St. Joseph, in the county of Buchanan and State of Missouri, have invented and produced a new and original Design for Hitching-Posts, of which the following is a specification, reference being had to the accompanying drawings, forming part thereof.

10 Figure 1 is a side elevation of my newly-designed hitching-post. Fig. 2 is a cross-section through the line x x ; and Fig. 3 is a view of the top part of the post, taken at right angles to that shown in Fig. 1.

15 My newly-designed hitching-post consists of a cylindrical tube or pipe, A, having at the top a spherical head, B, with collar B' at its lower edge, and an eye, B', at the junction of the head and collar, a base-flange, D, which rests upon the sidewalk, and ornamental collars C C between the head and the base-flange. The lower end of the post has four wings or blades, E, at right angles, which run from the base-flange D to a sub-base flange, F, and at 25 the point where blades E join the base-flange D the angle between the blades E is filled in.

The leading feature of the design is the fol-

lowing conjoined or associated elements regarded as a whole: the straight cylindrical portion A, the base-flange D, collars C C and 30 B', the spherical head B, and the eye B', arranged between the head B and collar B'.

I claim—

1. The design for a hitching-post, consisting of the straight cylindrical tube A, surmounted 35 by a spherical head, B, with adjacent collar B', and eye B' at the junction of the head and collar, the base-flange D, and collars C C, disposed on the cylinder between the base-flange and the head, substantially as shown and described.

2. The design for a hitching-post, consisting of the straight cylindrical tube A, surmounted by a spherical head, B, with adjacent collar B', and eye B' at the junction of the head and 45 collar, the base-flange D, collars C C between the base-flange and head, the right-angular blades E, with filled angles G, and the sub-base flange F, substantially as shown and described.

JULIUS FRANCIS ROGERS.
